(57) **CLAIM**

I claim the ornamental design for a golf putting rail, as shown and described.

DESCRIPTION

FIG. 1 is a top plan view thereof;

FIG. 2 is a side elevational view thereof, the undisclosed opposite side being identical;

FIG. 3 is a bottom plan view thereof;

FIG. 4 is an enlarged end view thereof, the undisclosed opposite side being identical; and,

FIG. 5 is a perspective view of FIG. 1.
